[57] CLAIM

The ornamental design for a floral foam holder for a vase, as shown and described.

DESCRIPTION

FIG. 1 is a perspective view showing the top and side of a floral foam holder for a vase embodying my new design;

FIG. 2 is an enlarged side elevational view thereof;

FIG. 3 is an enlarged top plan view thereof;

FIG. 4 is an enlarged bottom plan view thereof;
FIG. 5 is a further enlarged fragmentary sectional view taken in the direction of the arrows on line 5—5 of FIG. 3;

FIG. 6 is a further enlarged fragmentary view showing a portion of the outer rim.
